TO THE PROSPERITY COMPANY, INC., OF SYRACUSE, NEW YORK, A CORPORATION
OF NEW YORK.

PRESSING-MACHINE CONTROL.

Application filed July 26, 1924. Serial No. 728,500.

This invention relates to power presses and particularly to garment and laundry pressing machines and has for its object a particularly simple and efficient mechanism by which the movable element or press head is preliminarily closed in advance of the final application of pressure thereto, and the preliminary closing movement is controlled by the power actuator whereby when the operator sets the machine in motion, the press head is preliminarily closed by itself as by gravity to a "safety first" position, that is, a position so close to the work between the pressing elements, that it is impossible for the operator to have his hands or fingers between the pressing elements, and whereby, if for any reason the pressing element is not brought down to the "safety first" position on account of obstructions, or for any other reason, the power will not be effectively applied to the movable pressing element but the power transmitting connections will merely idle.

The invention consists in the novel features and in the combinations and constructions hereinafter set forth and claimed and described.

Figures 1 and 2 are side elevations of this pressing machine, the same being shown as open in Figure 1 and as closed in Figure 2.

Figure 3 is a fragmentary front elevation thereof.

Figure 4 is a detail view of the clutch mechanism.

Figure 5 is a plan view of the cam.

This pressing machine comprises generally coöoperating pressing elements, one of which is movable toward and from the other, a power member, connections operated by the power member to apply pressure to the movable element, such connections being normally arranged in ineffective position to transmit power and movable into effective position by a preliminary closing movement of the movable element, independent of the power member, the movable element initially closing automatically here shown as by gravity, an actuator for the power member, and means operated by the actuator for controlling the preliminary closing movement of the movable element.

I have here shown my invention as embodied in a conventional type of pressing machine comprising a stationary pressing

element or buck 1, a movable pressing element or head 2, movable toward and from the buck 1 the buck 1 being mounted upon a bracket 3, which in turn, is mounted upon a frame including a table 4 supported by legs or pedestals 5, 6. The head 2 is usually carried by a lever or a yoke 7 pivoted at 8 between its ends to a standard 9 extending upwardly of the rear leg 6 of the frame, the head 2 being carried on the front arm of the lever 7 and the rear arm having a counter weight 10 thereon.

11 is the power member, and the connections operated by the power member, in addition to the lever 7, as here illustrated, include a toggle including a link 12 pivoted at 13 to the rear arm of the lever 7, and a link 14 pivoted at 15 to the link 12 and at 16 to the frame or rear leg 6 thereof, the link 14 normally extending downwardly and forwardly from the pivot 15. The connections further include a third link 17 pivoted at 18 to the power lever 11 and connected at 19 to a downward extension 20 of the link 12, by a pin-and-slot connection, the pin 21 being on the extension of the link 12 and the slot 21^a being formed in the link 17.

The power member 11 is a forwardly and rearwardly extending lever pivoted between its ends to the frame, and the link 17 is pivoted to the rear arm of the lever 11. Usually the power lever 11 and toggle link 14 are mounted upon the same pivot 16. These connections are normally arranged in the position shown in Figure 1 and obviously if power is applied to the lever 11, the connection 17 will idle, that is, the power of the lever 11 will be ineffective on the toggle and the head 2. However, when the links 12 and 14 have been moved to nearly straightened position and the link 17 to nearly upright position, the power of the lever 11 will be applied to the link 17 in a right angular direction to the power lever, and the pin 21 now being at the lower end of the slot 21^a is thrust on by the link 17 and will cause the joint of the toggle to move nearer the dead center line of the toggle and thus apply pressure to the head 2.

The construction thus far described per se forms no part of this invention and in so far as my invention is concerned, any connections or toggle linkage which moves from an ineffective position to an effective

position by a preliminary closing of the press head, may be used.

The head 2 is constructed to close automatically and for this purpose, the head or 5 the weight on the front arm of the lever 7 is greater than the weight on the rear arm of the lever 11 so that the lever tends to move by gravity towards closed position.

The actuator for the power lever 11 as 10 here shown comprises an intermittently movable shaft 22 having a cam or an eccentric 23 thereon, which coacts with a face 24 on the front arm of the lever 11. The means operated by the actuator for controlling the preliminary closing movement 15 of the movable element is also operated by this actuator. Such controlling means as here shown comprises eccentric or cam means as a crank arm 25 mounted on, and 20 fixed to, the eccentric pin 23, and a link 26 pivoted at 27 to crank arm 25 and connected to the movable element, or some part 25 movable therewith by a lost motion or pin-and-slot connection. The link 26 is here shown as connected to the toggle link 12 by a pin-and-slot connection, the link 12 being shown as formed with a bracket 12^a on its front side, which bracket is formed 30 with the forwardly and rearwardly extending slot 28 in which works the pin 29 on the rear end of the link 26. This bracket 12^a coacts with the stop 14^a when the press is opened to limit the opening movement 35 thereof, this stop 14^a being provided on the link 14 in position to engage the bracket 12^a as seen in Figure 1 when the press is open.

The angle of the crank 25 is such that 40 when the press head is open or in its position shown in Figure 1, the pin 29 is at the rear end of the slot 28 and thus prevents forward movement of the link 12, and hence 45 downward movement of the head 2. However, when the shaft 22 starts to make a half revolution, the crank being on the eccentric withdraws the link 26 away from the link 12 so that the head is free to close by gravity before the eccentric finally depresses the lever 11. In other words, upon 50 the initial movement of the shaft 22, the link 26 tends to move away from the toggle link 12 of the press head 2. The power lever is held against the cam to follow it by a 55 spring 11^a.

There are thus two sets of connections operated by an actuator common to both, one set operating to permit a preliminary closing movement of the press head and to permit the other set to be brought from ineffective to effective position, and the other set operating to transmit the pressure to the head after being first brought into effective position by such preliminary closing movement.

60 The mechanism for intermittently ac-

tuating the shaft 22 comprises a constantly running electric motor 30 and suitable gearing and periodic clutch mechanism between the shaft 31 of the motor and the shaft 22, such gearing and clutch mechanism being 70 located within the housing 32 which is suitably supported by the frame of the machine.

The gearing comprises a worm 33 mounted on the motor shaft 31 and meshing with the worm wheel 34 mounted on or concentric with the shaft 22 and rotatable relatively thereto. The clutch mechanism comprises a shiftable clutch section 35 mounted on and rotatable with the shaft 22 and clutch pins 36 shiftable by the clutch section 35 into and out of holes 37 formed in the wheel 34. The pins are guided in a suitable guide disk 38 mounted on shaft 22 adjacent to wheel 34, the ends of the pins being tapered and also the holes 37 being complimentally tapered so that the pins quickly release themselves, when the force tending to hold them in, is released. The thrust of the clutch section 35 is not transmitted directly to the pins, but to the pressure ring 39 slidable on shaft 22, through which pressure ring the pins slide. The ring thrusts against shoulders 40 on the pins. The shifting motion of the section 35 is yieldingly transmitted to the ring 39 through comparatively light springs 41. A 95 heavy main spring 42 shifts the clutch section 35 to its "out" position. The clutch section 35 is shifted in position against the springs 41, 42 by a shifter arm or lever 43 pivoted at 44 to the frame and operated as 100 will be hereinafter described.

This lever 43 has an arm 45 extending upwardly and inwardly under the table 4 where it is connected to mechanism for actuating it to throw the clutch section 35 into 105 engaged position. The mechanism for actuating the lever 43 is here shown as a solenoid 46 located within a suitable housing 47, the core 48 of the solenoid being connected to the horizontal arm 45 of the 110 lever 43 by a pin-and-slot connection 49. The solenoid may be of any suitable form, size and construction and as that here shown is a commercial article of manufacture, further description is thought to be unnecessary, it being sufficient to bear in mind that when the coils of the solenoid are energized, the core 48 is pulled downwardly moving the lever 45 in such direction as to shift the clutch section 35 inwardly and hold it in 115 while the press head is closing. The current through the solenoid is controlled preferably by two push buttons 50 connected in series with the solenoid so that both push buttons must be depressed and held depressed to hold the solenoid energized.

To close the press, the push buttons 50 are operated causing the clutch section 35 to be thrust to the left against the spring 42 and thus carry the pins 36 into the holes 37 120

of the driving worm wheel 34 so that the shaft 22 turns with the wheel 34, as long as the operator holds the push buttons depressed. The initial part of the turning of the shaft 22 causes the link 26 to tend to move away from the toggle link and permit the press head 2 to close by gravity, and in so doing bring the toggle links 12, 14 and the link 17 into effective position so that the movement of the power lever 11 by the eccentric 23 will apply pressure to the head 2. When the head 2 is closed as described the operator removes his fingers from the push buttons 50 and the head will remain closed as long as desired. To open the press, the operator again presses both buttons 50 and the shaft 22 makes another half revolution. However, during the opening movement of the press, it is not necessary to hold the push buttons 50 depressed, as means is provided for holding the clutch in during the half revolution of the shaft 2 which permits the opening of the press. This means is here shown as a cam ring 51 carried by the casing 32 concentric with the shaft 22 and a follower 53 on the face of the clutch section 35 opposed to the cam ring. This cam ring is provided with a low semi-circular portion or half 54 and a high semi-circular portion or half 55. When the press is open the follower is at the starting end of the low surface 54 and when the push buttons are depressed and the solenoid energized, the follower moves away from this low portion 54 and is held away from the same as long as the push buttons are held depressed.

During the closing of the press, the follower moves along the low face 54 but is spaced apart therefrom and in the event the operator removes either or both hands from the push buttons, obviously, the spring 42 will react and throw the clutch section "out" thereby disconnecting the pins from the drive wheel 34.

The operator determines by the feel of the machine, when the press is closed and the power applied and removes one or both hands from the push buttons.

In opening the press, a momentary depression of the push buttons will again cause the solenoid to throw the shiftable clutch section 35 "in" and during the initial part of the rotation of the shaft 32, the follower 53 engages the high surface 55 of the cam ring 51 and thus the clutch is automatically held "in" while the shaft 22 is making the half revolution to open the press, the clutch section 35 being shiftable automatically "out" by the spring 42, when the follower reaches the end of the high surface 55 and moves off such end to the low surface 54. The construction of the clutch forms no part of my invention and is the invention of a person other than applicant,

and hence applicant makes no claim herein thereto. Also applicant makes no claim herein to the solenoid and the two push buttons control illustrated herein as such combination forms the subject matter of my pending application Sr. No. 724,045 filed July 31, 1924.

What I claim is:

1. A pressing machine comprising cooperating pressing elements, one of which is movable toward and from the other, a power member, connections between the power member and the movable element normally arranged in ineffective position and movable automatically into effective position by a preliminary closing movement of the movable element independently of the power member, an actuator for the power member and means for normally holding the movable element from moving toward closed position, said means being connected to the actuator to be moved out of operative position and permit the movable element to close and said connections between the power member and the movable element to come into effective position.

2. A pressing machine comprising cooperating pressing elements, one of which is movable toward and from the other, the movable element having the weight thereof arranged so that said element moves by gravity toward closed position, a power member for applying pressure to the movable element, connections between the power member and the movable element normally arranged in ineffective position and movable automatically into effective position by a preliminary closing movement of the movable element independently of the power member, an actuator for the power member, and means operated by the actuator for normally holding the movable element from closing movement and movable out of holding position to permit the movable element to complete its closing movement before said actuator has effectively actuated the power member and said connections.

3. A pressing machine comprising cooperating pressing elements, one of which is movable toward and from the other, a power member, connections between the power member and the movable element normally arranged in ineffective position and movable automatically into effective position by a preliminary closing movement of the movable element independently of the power member, a cam actuated by the shaft and cooperating with the power member, a second cam associated with the shaft and connections operated by the second cam for normally holding the movable element from closing movement and movable to permit the preliminary closing movement of the movable element in advance of the final ac-

tuation of the power member by the first cam.

4. A pressing machine comprising cooperating pressing elements, one of which is movable toward and from the other, a power member, connections between the power member and the movable element normally arranged in ineffective position and movable into effective position by a preliminary closing movement of the movable element independently of the power member, an intermittently movable actuator coacting with the power member, connections operated by the actuator for holding the movable element from closing movement and shiftable during the initial movement of the actuator to permit the closing movement in advance of the bringing of said connections into effective position, the connections operated by the actuator for holding the movable element coacting with a portion of the connections between the power member and the movable element.

5. A pressing machine comprising cooperating pressing elements, one of which is movable toward and from the other, a power member, connections between the power member and the movable element to actuate the movable element including a toggle normally arranged in ineffective position and movable into effective position by a preliminary closing movement independently of the power member, an intermittently movable actuator having means coacting with the power member and connections between the actuator and the toggle to normally hold the toggle from closing movement and the movement of the movable element toward closed position, said movable element being arranged to move when unrestrained toward closed position, the last mentioned connections being operable to release the toggle to permit it to straighten into effective position before the power of the actuator is effectively applied to the power member.

6. A pressing machine comprising cooperating pressing elements, one of which is movable toward and from the other, a power member, connections between the power member and the movable element normally arranged in ineffective position and movable into effective position by a preliminary closing movement of the movable element independently of the power member,

an actuator comprising an intermittently movable shaft having an eccentric coacting with the power member, a crank arm fixed to the eccentric and connections operated by the crank arm to normally hold the movable element from preliminary closing movement, said connection between the crank arm and the movable element including a lost motion connection whereby said connections move in advance of the closing movement of the movable element and permit said movable element to close.

7. A pressing machine comprising cooperating pressing elements, one of which is movable toward and from the other, a power member, connections between the power member and the movable element normally arranged in ineffective position and movable into effective position by a preliminary closing movement of the movable element independently of the power member, an actuator comprising an intermittently rotatable shaft having an eccentric coacting with the power member and a crank arm fixed to the eccentric and a link pivotally mounted on the crank arm and connected to a portion of the former connections by a pin-and-slot connection to normally hold the movable element from movement toward closed position and movable during actuation of the shaft in advance of the connections which actuate said element.

8. A power machine comprising coacting pressing elements, one of which is movable toward and from the other, and having a preliminary closing movement, an intermittently movable actuator, a connection between the actuator and the movable element to effect the preliminary closing movement thereof and to effect the opening movement thereof and a second connection between the actuator and the movable element arranged to be moved by such preliminary movement, from an ineffective position to an effective position to transmit the pressure from the actuator to the movable element when such connections are brought into effective position.

"In testimony whereof, I have hereunto signed my name, at Syracuse, in the county of Onondaga, in the State of New York, this 27th day of June, 1924.

PHILIP N. BRAUN.
